UNITED STATES PATENT OFFICE.

VICTOR E. EDWARDS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

METHOD OF TREATING METAL RODS.

1,232,014.

Specification of Letters Patent.

Patented July 3, 1917.

Application filed November 10, 1915. Serial No. 60,806.

To all whom it may concern:

Be it known that I, VICTOR E. EDWARDS, a citizen of the United States, residing at Worcester, in the county of Worcester and 5 Commonwealth of Massachusetts, have invented a new and useful Improvement in a Method of Treating Metal Rods, of which the following, together with the accompanying drawings, is a specification.

10 The present invention relates to a method of treating metal rods, and has particular reference to the treatment of wire rods as they emerge from the finishing pass of a rolling mill, whereby cooling of the same, or 15 treatment designed to arrest or prevent oxidization thereof, in any well known manner, is facilitated.

The invention resides in the several steps employed to expose, as completely as possible, the entire surface of each rod to the action of the selected cooling or deoxidizing medium, in such a manner as to render most convenient the subsequent handling and transportation of the rod so exposed. The 25 features of my improved method of treatment are fully set forth in the following description, reference being had to the accompanying drawings which illustrate a preferred arrangement of apparatus for carrying 30 ing the several steps into practice, and in which—

Figure 1 is a side view, partly in section, of said apparatus.

Fig. 2 is a fragmentary sectional view, 35 on the line 2—2, Fig. 1.

Fig. 3 is a diagrammatic representation of the position which a rod assumes during its treatment by the reducing agent.

Similar reference characters refer to similar parts in the different figures.

Heretofore, in the treatment of wire rods emerging from the finishing passes of a rolling mill, it has been the usual practice to coil the rods, while hot, into conveniently 45 handled bundles, and, if desired, to cool said bundles by passing them through a chamber containing a non-oxidizing atmosphere, in order to prevent the further oxidizing action of the air during the period of cooling. 50 However, it is clear that such treatment, while serving to arrest further oxidization of the rods, does not affect the oxid already formed on the surface of the rods by reason of their exposure to the atmosphere

while being rolled, and previous to their introduction, in coiled form, into the cooling chamber. It is clear, moreover, that the compact coiling of the rods, as heretofore practised, prevents the complete exposure of the rods during the period of cooling, and thus has rendered useless, in the past, any attempt to subject the coils to a deoxidizing or reducing atmosphere for the purpose of removing the oxid already formed on the rods. 55

The present invention, as hereinafter particularly described, contemplates a method of treatment by which the rod, emerging from the mill, is so coiled, while hot, that there is practically a complete exposure of its surfaces during the period of cooling, 60 whereby the action of a deoxidizing medium may be rendered effective with respect to the entire surface of the rod, serving not only to arrest completely all further oxidization, but also to remove oxid which has already 65 formed, by exposing to the air during rolling. Furthermore, the improved method employed enables the rods, after cooling as above described, to be formed readily into compact coils, suitable for subsequent handling and transportation in the usual manner. 70

The particular arrangement of apparatus which I deem preferable for carrying my improved method into practice will now be 75 described in detail, but it is to be understood that such apparatus is illustrative merely, and that my invention is not limited to the herein described or any other particular form of apparatus. 80

Referring to Fig. 1, the numeral 1 designates a stand of rolls constituting the finishing pass of a rolling mill, the same being of ordinary construction, and equipped with the usual delivery guide 2. In advance of 85 the stand of rolls 1, a bracket 3 provides a vertical bearing 4 for a shaft 5, rotated by any well known means, such as a pulley 6 and belt 7, from the shaft which drives the finishing rolls. Below the shaft 5 the 100 bracket 3 has a shelf 8 which provides a bearing socket, in axial alinement with shaft 5, for a spherical enlargement 9 formed intermediate the ends of a rod 10. The upper end of rod 10 has a spherical tip 11, received 105 within an axially offset socket in the lower end of shaft 5. Near its lower end the rod 10 is enlarged, as at 12, to form a curved tu-

bular guide section, the lower end of which projects through a floating flange or washer 13, for a purpose hereinafter set forth.

Above this tubular section 12 a curved 5 tubular guide member 14 is pivoted at 15 to the rod 10 and extends rearwardly and upwardly into telescoping relation to the delivery guide 2, being supported at its other end upon a bracket 16, which provides 10 a guideway 17 for said end of member 14 to compel its reciprocation in alinement with the delivery guide 2. As will be apparent, the rotation of the shaft 5 imparts a circular movement, of relatively small radius to the lower end of the rod 10; the 15 pivotal connection 15 of the member 14 with said rod likewise moves in a circle, of still smaller radius, thereby reciprocating the member 14 back and forth in the guideway 17. By the operation of the above described 20 mechanism, a rod emerging from the finishing pass of the mill is directed downwardly through the curved closed conduit constituted by the delivery guide 2, the member 14 25 and the lower end 12 of the rod 10; the movement of said lower end, in a circular path, and at a lower linear velocity than the velocity imparted to the rod by the rolls 1, causes the rod to be laid in circular turns 30 of greater radius than the circular path of the lower end 12 of rod 10.

Below the lower end 12 of the coil laying member 10 is disposed a coil supporting surface, which, in the present instance, takes 35 the form of a constantly moving conveyer belt or apron 20, which may be of the endless type, passing around rolls 21, 21. The speed of this conveyer is so related to the speed of the laying mechanism, that each 40 turn of the rod laid by the above described coiling mechanism becomes offset rearwardly of and, therefore, non-concentric to the next preceding turn, but overlaps the same, as shown clearly in Figs. 1 and 3, the result 45 being that practically the entire surface of a rod so coiled, except at the two points where adjacent turns intersect each other, is exposed. In this way, uniform cooling of the rod is insured, as the coil thus formed, 50 comprising a series of non-concentric inclined turns, is carried forward on the conveyer. Furthermore, by inclosing the conveyer in a tunnel 22, having preferably a water cooled roof 23, with a frusto-conical 55 entering passage 24 for the rod which is being laid, each rod so coiled may be uniformly and completely exposed to the action of a deoxidizing medium, introduced to the tunnel through a suitable pipe 25. The 60 floating flange 13 surrounding the rotating rod 10 covers the upper end of passage 24 to prevent the escape of the treating medium from the tunnel.

The removal of each coil from the conveyer, at the extreme forward end thereof,

is accomplished by an arm 26, pivoted at 27 on a movable truck 28, and having an extension 29 which is supported, normally, so as to intercept the successive non-concentric turns of each coil as they reach the extreme 70 end of the conveyer, causing successive turns of the coil to be strung upon said arm, as the supporting surface of the conveyer moves downwardly around the forward roll 21. In this way the support of 75 the coil is transferred from the conveyer to the extension 29, the successive turns of the coil assuming, by gravity, a regular concentric relation with respect to each other as the support of the conveyer is withdrawn; 80 when the arm is tipped up, about its pivot, the turns are compacted thereon, by gravity, thereby forming a coil suitable for handling and transportation in the usual manner. 85

I claim,

1. The within described method of treating wire rods, comprising the coiling of a rod in successive non-concentric turns, subjecting the rod so coiled to a treating medium, and assembling said turns in concentric form. 90

2. The within described method of treating wire rods, comprising the advancement, by longitudinal movement, of a rod, the 95 coiling of said rod on a supporting surface, with each turn thereof overlapping, but offset from, the preceding turn of the coil, and the cooling of the rod so coiled in a reducing atmosphere. 100

3. The within described method of treating wire rods, comprising the coiling of a rod on a continuously moving supporting surface, whereby each turn of the coil is laid eccentrically to the next preceding turn, 105 and the cooling of the rod so coiled in a reducing atmosphere. 100

4. The within described method of treating wire rods, comprising the laying, upon a support, of a rod in a coil having its successive turns eccentric, the cooling of said coil, and the assembling of said turns in substantially concentric form, by the movement of said support. 110

5. The within described method of treating wire rods, comprising the advancement, by longitudinal movement, of a rod, the progressive coiling of said advancing rod on a supporting surface, the movement of said supporting surface during the coiling 115 of said rod, to offset successive turns of the coil, the cooling of said coil during said movement, and the assembling of said turns in substantially concentric form, by the subsequent movement of said supporting 120 surface. 125

6. The within described method of treating wire rods, comprising the laying of a continuous rod upon a support, in such a manner as to expose substantially the en- 130

tire surface thereof, the treatment of the rod so laid by a reducing medium, and the compacting of said rod into a coil having concentric convolutions, by movement of 5 said support.

7. The within described method of treating wire rods, comprising the delivery of rods from a mill into a reducing atmos-

sphere, and the coiling and cooling of said rods in said reducing atmosphere. 10

Dated this first day of November, 1915.
